VALVED FLOOR DRAIN

Zachary Harry Smith, Mishawaka, Ind.

Application September 21, 1939, Serial No. 295,874

5 Claims. (Cl. 182—31)

This invention relates to valved floor drains, and more particularly to a construction by which the floor drain in the basement of a building connected with a drain or sewer pipe may be selectively opened for free drainage, or positively closed against back pressure in the line with which it is connected.

Various devices of this character and for this purpose have been devised heretofore, but in each of those of which applicant has knowledge, some serious obstacle to successful, practical, or economical use is involved. Thus various attempts have been made to incorporate an automatic valve in connection with a drain wherein the valve operates on the check valve principle, being suspended freely below a valve opening and adapted to be raised to closed position by back water pressure in the drain pipe. Since most of the valves of this type operate on the principle of a valve float their action is not positive, and because they work against gravity and are subject to sticking, as through accumulation of rust and the like, they have not proved satisfactory. Various types of positive valves have also been developed for this purpose, but these have generally been quite complicated in construction, and hence expensive to manufacture and install.

It is therefore the primary object of this invention to provide a novel and simple valve construction for use with a floor drain.

A further object is to provide a device of this character wherein the cover for the drain bowl or cup is fixedly secured to said bowl or cup, whereby the cover may carry pressure applying means associated with a valve member adapted to be applied against the outlet of the bowl or cup.

A further object is to provide a device of this character wherein a valve member has a rockable connection with an operating or pressure applying member, so that the valve member is free to assume an operative sealing position in relation to the outlet of the drain, which, being generally formed of cast metal, is subject to irregularities.

A further object is to provide a device of this character including a positive action valve wherein all the parts thereof are normally positioned at or below the level of the floor and of the upper surface of the cover plate of the floor drain.

Other objects will be apparent from the description and appended claims.

In the drawing:

Fig. 1 is a vertical transverse sectional view of the device taken on line 1—1 of Fig. 2.

Fig. 2 is a top plan view of the device.

Fig. 3 is a fragmentary vertical sectional view of a modified construction of the device.

Referring to the drawing, which illustrates the preferred embodiment of the invention, the numeral 10 designates a bowl or housing which is adapted to be set in the floor with its upper edge substantially flush with or slightly below the surface of the floor. At its center the bowl has an opening 11 defined by a cylindrical projecting portion 12 which is adapted for connection with a drain pipe or sewer pipe 13 in any desirable or suitable manner. In the embodiment illustrated in Fig. 1, an upwardly projecting annular rib 14 is formed at the margin of the bowl opening 11 for purposes to be hereinafter set forth.

A cover plate 15 provided with suitable drain apertures 16 fits on an interiorly projecting flange 17 of bowl 10 adjacent the upper end of the bowl. Cover 15 is adapted to be fixedly secured to place on flange 17 by means of screws or other securing members 18. Cover 15 has a sleeve 19 formed integral therewith centrally thereof and depending therefrom. Ribs 20 serve to reinforce said plate and sleeve. An interiorly screw threaded opening 21 is formed centrally in plate 15 and extends through sleeve 19, said opening 21 preferably being axially aligned with opening 11.

A shaft 22 is screw threaded in opening 21 and is provided at its lower end with a ball 23. The upper end of shaft 22 is provided with a socket 24 into which a suitable tool may be inserted for rotating the shaft.

A valve head 25 is provided with a socket member 26 at its upper end adapted to fit around ball 23. As illustrated in Fig. 1, valve head 25 terminates in a substantially flat plate portion 27 having a substantially flat lower surface. A comparatively thin sheet of rubber, artificial rubber, such as "Durene" or "Neoprene", or some other suitable yielding material adapted for sealing purposes, is fixedly secured to the lower flat face of valve head 25. The size of the lower portion 27 of the valve head and of the sealing member 28 is slightly greater than the diameter of the marginal ridge 14 of the bowl.

It will be seen from the above that when shaft 22 is rotated to force the same downwardly, valve member 25 will be positively pressed and forced against ridge 14 of the bowl 10. The bowl 10 is usually formed of cast metal and hence is subject to irregularities and inaccuracies of manufacture. This is partly compensated for by the

resilient or yielding character of the sealing material 28. However, in the event of inaccuracies or irregularities which are greater than those which the elasticity of material 18 may readily compensate for, the ball and socket connection between shaft 22 and valve head 26 comes into play. In fact, the combination of the universal joint connection between the shaft and valve head with the elastic character of the sealing face member 28 serves to provide a positive seal for opening 11 with minimum deforming or compressing of member 28, thereby serving to increase the effective life of the material 28.

The shaft is preferably of such length that when the valve is urged into sealing position thereby the upper end of the shaft will be positioned at or below the level of the upper end of the plate 15, and when the valve has been opened the shaft will not project above the upper surface of plate 15 to any material extent. In this way danger that the device may constitute an obstacle over which a person might stumble is entirely avoided, and a substantially flush surface is provided at all times. At the same time the provision of the tool socket 24 in the upper shaft end provides means whereby the valve may be readily and conveniently actuated.

A slightly modified construction is illustrated in Fig. 3. The modification exists essentially in the shape of the valve head 30, which is of part spherical formation so that the shape of the resilient sealing member 31 thereof is substantially curved or rounded. The construction in all other respects is the same as in the preferred embodiment and the same reference numerals are applied.

The principal advantage of this modified construction is that the ridge 14 of the preferred embodiment may be entirely eliminated, thus avoiding the necessity of having some water standing in the bowl 10 to the level of the ridge 14, as occurs in the preferred embodiment. This is achieved by virtue of the curved shape of the valve head on a small radius than the bowl curvature so that the valve head may extend slightly into outlet opening 11 of the bowl, while its outer marginal portion projects outwardly of the opening 11 and above the adjacent portion of the

bowl 10; thus preventing interference from the bowl to the solid seating of the valve head, which is not possible with a flat valve. The same ball and socket connection 23, 28 between the shaft 22 and head 30 are provided to give the advantage of self-seating of the valve head for compensation with irregularities and inaccuracies of the bowl 10.

I claim:

10. 1. In a valved floor drain, a perforated cover plate adapted to be fixedly secured to the upper end of a cup-shaped drain bowl, said plate having a downwardly projecting internally screw threaded collar integral therewith, a shaft threaded in said collar with its upper end normally positioned at or below the upper face of said plate, and a valve member having a universal joint connection with the lower end of said shaft.
15. 2. In combination, a floor drain bowl having an outlet communicating with a drain pipe, an apertured cover fixedly secured to said bowl, a valve member adapted to seal said outlet, and operating means carried by said cover for pressing said valve in sealing relation to said outlet, said means having a ball and socket joint connection with said valve.
20. 3. The combination defined in claim 2, wherein said valve has a rounded sealing surface.
25. 4. The combination with a floor drain having a cup-shaped housing with an outlet at its lower end for communication with a sewer, of an apertured plate covering the open end of said housing and secured thereto, a shaft threaded in said plate in axial alignment with said outlet, and a valve member carried by said shaft and adapted to seal said outlet, said valve member having a ball and socket connection with said shaft to positively seat at said outlet and to accommodate itself to irregularities of said outlet.
30. 5. In combination, a floor drain bowl having an outlet adapted to be connected with a drain pipe, a valve member adapted to seal said outlet, operating means carried by a fixed part of said bowl and having a ball and socket connection with said valve for pressing said valve in sealing relation to said outlet.

ZACHARY HARRY SMITH.
